CLAIM

We claim the ornamental design for hardware for luggage, as shown and described.

DESCRIPTION

FIG. 1 is a perspective view of our design for hardware for luggage showing a wheel and glide assembly for luggage.

FIG. 2 is a bottom view thereof.

FIG. 3 is a top view thereof.

FIG. 4 is a front view thereof.

FIG. 5 is a rear view thereof; and,

FIG. 6 is a right side view thereof, the left side view thereof being a mirror image.

The broken line showing of hardware detail seen in FIGS. 2 and 5 is included for the purpose of illustrating portions of the hardware for luggage and forms no part of the claimed design.
